UNITED STATES PATENT OFFICE.

ROBERT GORTON, OF NEWTON, MASSACHUSETTS.

GARMENT-SUPPORTER.

SPECIFICATION forming part of Letters Patent No. 633,583, dated September 26, 1899.

Application filed March 1, 1899. Serial No. 707,380. (No model.)

To all whom it may concern:

Be it known that I, ROBERT GORTON, a citizen of the United States, residing at Newton, in the county of Middlesex and State of Massachusetts, have invented certain new and useful Improvements in Garment-Supporters, of which the following is a specification.

My invention relates to the class of hose-supporters shown in my Patent No. 552,470, of December 31, 1895, in which the hose is held between a stud or button and a loop that extends over the button and the intervening portion of the hose.

In the hose-supporter shown in my patent just referred to the stud or button is made wholly or partially of rubber or similar soft or yielding material, one object being to prevent the slipping and consequent chafing or tearing of the hose, which occurs when a metal button is employed. Although the improvements set forth in my prior patent entirely did away with the chafing and tearing caused by the slipping of the button in the prior constructions when a smooth metallic button was employed, I find that considerable chafing or wearing of the hose is caused by the rubbing of undergarments against that part of the hose which is stretched across the button. This is particularly true when the stockings fit snugly and are made of thin or soft material and when the garments hang close to the legs of the wearer. To obviate this objection, I provide a hood or casing which extends over the top of the button and shields or covers that part of the hose which is stretched on the button.

I am aware that heretofore a hose-supporter of the same general kind as mine has been provided with a hood or shield which covers that portion of the material stretched over the button; but in the prior constructions the hood, secured to the loop by either its upper or lower end, was apt to be bent out of place and presented an edge liable to tear the garment or was difficult of attachment. By my improvements the hood is made strong by making it in the form of an arch extending over that portion of the loop in which the button rests and by having its two opposite ends firmly secured to the sides of the loop, the formation being such as to present

smooth surfaces that are not liable to catch the garment or tear it.

In the accompanying drawings, Figure 1 shows a front elevation of a garment-supporter embodying my improvements. Fig. 2 is an end or bottom view thereof. Figs. 3, 4, and 5 are perspective views of several modifications. Fig. 6 is a transverse section through a hose-supporter button and a loop provided with one of my improved hoods or shields, and Fig. 7 shows a transverse section through one of my improved hoods and illustrates how it may be secured to the loop.

The loop A (shown in Fig. 1) is attached to the webbing B in the usual way, and the key-hole slot a is preferably provided with the usual rib or lining a'.

The stud or button C is attached to the usual base-piece c and may be of usual construction, being made of any suitable material. I prefer, however, to make the button principally of rubber or some soft yielding or elastic material. In the construction shown the part c' of the button is made of rubber and is secured to the base-plate c by a rivet c², provided with a head c³, which may be made concaved or dish-shaped.

In the use of a garment-supporter such as I have just described the hose is clamped between the button and the inner side walls of the loop and a portion of the fabric is stretched over the head of the button. This portion of the fabric is exposed to considerable wear, the undergarments of the wearer rubbing against it, and by long-continued use the fabric stretched over the hood will be chafed, roughened, and worn. To obviate this, I provide a hood or shield D, which extends above and over the button and prevents the undergarments from coming in contact with the button or the fabric stretched over it.

In Fig. 1 the hood is shown as being formed by two ears d d, projecting laterally from the loop A at its lower end and bent over until their ends meet above the button. In order to produce a neat appearance and save metal, the ears may be cut away at d'. The edges d² come close together and are arranged a sufficient distance above the top of the button to permit the hose to lie between the hood and the button. The edges d² may be straight

abutting edges, and in order to hold them securely together a rivet E is employed. This rivet is preferably made hollow, so that the concaved top of the rivet c^2 may be exposed to view. This affords a strong construction. 5 All of the edges may be curved or made smooth. They are not liable to catch or chafe the hose or other garments, and the hood holds the undergarments of the wearer away from the hose stretched over the button. 10 It is not absolutely necessary that a rivet E should be used. The abutting edges d^2 may lie close together and may be curved, as shown in Fig. 3, the ears d being made of sufficiently stiff metal to retain their place, not being liable to be bent out of shape. 15

Instead of forming the hood from the same piece of metal of which the loop A is formed it may be made of a separate piece or pieces 20 and secured to the loop.

In Fig. 4 the loop D is shown as made of one piece of metal, the ends d^4 being passed through slots a^2 in the loop and bent at d^5 , and, if preferred, they may be there soldered. 25 In Fig. 5 the hood D is shown as made of a single piece of metal, the central portion being concavo-convex and having an opening d^6 immediately over the concave head of the rivet. The legs of the hood have their 30 ends extended through slots in the loop and bent and firmly secured thereto.

The manner of securing the hood to the loop when it is made of a separate piece or separate pieces of metal is indicated clearly in 35 Figs. 6 and 7.

The hood is preferably in each instance arranged some distance above the lower end of the loop, so as to leave the portion a^3 thereof exposed. The hood is also in each instance 40 so arranged on the loop that it will occupy a position immediately over the button when the button is drawn down to the position it occupies when the hose is attached. The hood is open at its upper end—that is, the end 45 next the upper end of the keyhole slot—so that the button can slide in the slot into and out of the hood.

I claim as my invention—

1. In a garment-supporter, a slotted loop provided with a hood open at its upper end 50 in line with the slot, extending transversely across the lower portion of the slot and joined to opposite sides of the loop.

2. In a garment-supporter, a slotted loop provided with a hood open at its upper end 55 in line with the slot, formed by wings extending from opposite sides of the loop made integral therewith, and bent across the lower end of the slot therein.

3. In a garment-supporter, a slotted loop 60 provided with a hood formed in two parts projecting from the sides of the loop near its lower end, and having the two ends which extend across the lower portion of the slot secured together.

4. In a garment-supporter a slotted loop provided with a hood formed in two parts projecting from the sides of the loop near its lower end, and having the two ends which extend across the lower portion of the slot 70 secured together by a hollow rivet.

5. A slotted loop provided with a hood open at its upper end, extending across the lower portion of the slot in the loop, and projecting from opposite sides of the loop, in combination with a button adapted to be moved longitudinally in the loop. 75

6. A slotted loop having a hood open at its upper end extending across the lower end of the slot, in combination with webbing attached to the loop, and a button attached to the webbing adapted to slide longitudinally in the slot of the loop. 80

7. A slotted loop provided with a hood formed in two parts joined to the sides of the 85 loop near its lower end and having the two ends which extend across the lower portion of the slot riveted together, in combination with a button attached to webbing and adapted to slide longitudinally in the slot. 90

In testimony whereof I have hereunto subscribed my name.

ROBERT GORTON.
